UNITED STATES PATENT OFFICE.

NORMAN LIPSKY, OF NEW YORK, N. Y., ASSIGNOR TO EMPIRE LIGHTING FIXTURE CO. INC., A CORPORATION OF NEW YORK.

DESIGN FOR A LANTERN BODY FOR LIGHTING FIXTURES.

Application filed April 5, 1926. Serial No. 17,185. Term of patent 7 years.

To all whom it may concern:

Be it known that I, NORMAN LIPSKY, a citizen of the United States, residing in the city of New York, county of New York, and State of New York, have invented a new, original, and ornamental Design for Lantern Bodies for Lighting Fixtures, of which the following is a specification, reference being had to the accompanying drawing, forming a part thereof.

The drawing is a perspective view of a design for lantern bodies for lighting fixtures.

I claim:

The ornamental design for a lantern body for lighting fixtures as shown.

NORMAN LIPSKY.
